CLAIM

The ornamental design for a safety enclosure, as shown and described.

DESCRIPTION

FIG. 1 is a front three-quarter perspective view embodying our new design;

FIG. 2 is a front elevation view;

FIG. 3 is a an enlarged front elevation view of the top portion of the inside panel shown for ease of illustration;

FIG. 4 is a an enlarged front elevation view of the bottom portion of the inside panel shown for ease of illustration; and,

FIG. 5 is a front elevation view as shown in FIG. 2 with the door shown in closed position.

1 Claim, 5 Drawing Sheets

FIG. 1

FIG. 2

IMPORTANT SAFETY INSTRUCTIONS READ AND FOLLOW ALL SAFETY INSTRUCTIONS

- Before using this equipment, read all instructions and cautionary markings on (a) this equipment, (b) any battery, and (c) any other equipment to be used in conjunction with this equipment.
- This cover contains important safety instructions, and therefore should never be removed from the equipment.
- Remove all jewelry, vehicles, rings, etc. before proceeding with installation or service.
- DO NOT touch any uninsulated parts of this equipment, especially the INPUT and OUTPUT connectors, as there is the possibility of electrical shock.
- During normal operation, batteries may produce explosive gas. Never smoke, use an open flame, or create arcs in the vicinity of this charger or the battery.
- Maintain at least 12 inches distance from all obstructions on the top, bottom and sides of this equipment. Allow sufficient clearance to open the front panel for servicing.
- Turn this equipment off before connecting or disconnecting the battery to avoid a shock hazard and/or equipment damage.
- Connect or disconnect the battery only when the battery charger is off to prevent arcing or burning.
- Do not charge all AC and DC inputs to the battery charger before servicing.
- Do not operate battery charger if it has been damaged in any way.
- Refer to qualified service personnel.
- Do not disassemble battery charger. Only qualified service personnel should attempt repair. Incorrect assembly may cause damage to this equipment or to its equipment or to the battery, electrical shock, fire or explosion.
- Do not install the battery charger outdoors, or in wet or damp locations, unless specifically ordered for that environment.
- Do not install the battery charger outdoors, or in wet or damp locations, unless specifically ordered for that environment.

COMPONENT LAYOUT / CONNECTION DIAGRAM

AC INPUT BREAKER

DC OUTPUT BREAKER

QUICK OPERATION

Startup

For installation instructions, see section 1 in the manual

► Turn on the DC breaker, labeled "DC OUTPUT BREAKER".
 ► Turn on the AC breaker, labeled "AC INPUT BREAKER".

Changing between Float and Equalize Modes

To learn how to use the equalize timers, see sections 2.2.4 and 2.3.3

► Press the key to toggle from Float mode to Equalize mode.
 ► Press again to toggle back to Float. The green or yellow indicator identifies the current mode.

Settings

► Float Voltage
 - Equalize Voltage
 - Equalize Timer
 - Current Limit

► High DC Voltage
 - Low DC Voltage
 - Current Limit

► Press the key. The DC VOLTS and FLOAT indicators light.
 and the digital display flashes the present float voltage setting.

► Press the or key until the digital display indicates the desired FLOAT voltage.

► Press the key to save the new setting internally.

► The EDIT sequence advances to the equalize voltage as shown

by the front panel indicators.

If you don't press any key for 25 seconds, the AT01 charger resumes normal operation automatically.

Repeat the above steps until you have set all parameters.

ERROR CODES

Below is a list of the error codes. See section 3.2 of the User's Manual for a full explanation of each error code.

Error Code	Explanation
E 01	R2 Rating resistor is open or defective
E 02	Short circuit on output
E 03	HVDC (High Voltage DC) Shutdown has occurred
E 04	Internal memory failure
E 05	Not used
E 06	Failure in Remote Sensing wiring
E 07	DC breaker is open, or internal or external output wiring is defective
E 08	Defective temperature compensation probe
E 09	Misadjusted current limit
E 10	Open internal feedback loop
A 01	Charger in Manual Equalize for more than 24 hours
A 02	Equalize Mode is inhibited
A 03	Battery problem detected

SAFETY SHIELD PART No. FB5000-00 REV. 01
